UNITED STATES PATENT OFFICE.

BENNETT B. SCHNEIDER, OF NEW YORK, N. Y.

DESIGN FOR A LAMP-SHADE.

SPECIFICATION forming part of Design No. 11,901, dated August 3, 1880.

Application filed July 8, 1879. Term of patent 14 years.

To all whom it may concern:

Be it known that I, BENNETT B. SCHNEIDER, of the city, county, and State of New York, have invented a new and original Design for 5 Lamp-Shades, of which the following is a specification.

My invention consists in a design for a lamp-shade comprising a cylindrical base portion, an overhanging shoulder, a body surmounting 10 the same and approximately parabolic in shape, an elongated neck, and a bell mouth, the whole vertical height of the shade being equal to or 15 superior to its largest diameter.

In the accompanying drawings, Figure 1 is 15 a side view of a shade embodying my design and a holder therefor. Fig. 2 is a side view of the shade-holder alone, and Fig. 3 is a side view of the shade alone.

Similar letters of reference designate corresponding parts in all the figures.

The shade-holder, which is of a kind commonly used, is composed of a cylindric base, A, an inwardly-extending neck or groove, B, an outwardly-flaring angular portion, C, a surmounting acutely-flaring angular portion, D, and an upturned cylindric portion or rim, E.

Referring now to the shade, G designates a cylindric base portion; H, an overhanging shoulder; I, a slightly-tapering conoidal or 20 approximately parabolic body or main portion of convex outline, and J a long tubular neck, terminating in an outwardly-rounded bell-

mouth, K. Preferably, at the junction of the main portion I and neck J there is formed a bead or bead-like molding, L.

35

The salient features of my shade are its rounded outline and its apparently greater height than diameter, and this appearance is due to the fact that the height of the shade is always equal to or slightly superior to its 40 greatest diameter.

A shade of this shape presents a very unique and tasty appearance, somewhat resembling that of an antique bottle or flask.

A shade of this kind and the shade-holder 45 above described present a very beautiful appearance, owing to the angularity of the shade-holder and the rounded outline and proportion of the shade.

What I claim as my invention, and desire 50 to secure by Letters Patent, is—

A design for a lamp-shade comprising the cylindrical base portion G, the overhanging shoulder H, the body I, surmounting the same and approximately parabolic in shape, the 55 elongated neck J, and bell-mouth K, the whole vertical height of the shade being equal to or superior to its largest diameter, substantially as herein shown and described.

BENNETT B. SCHNEIDER.
